UNITED STATES PATENT OFFICE.

WILLIAM D. KAIN, OF AMESBURY, MASSACHUSETTS.

DESIGN FOR AN INDICATOR-BODY.

SPECIFICATION forming part of Design No. 21,523, dated May 10, 1892.

Application filed March 16, 1892. Serial No. 425,183. Term of patent 3½ years.

To all whom it may concern:

Be it known that I, WILLIAM D. KAIN, a citizen of the United States, residing at Amesbury, in the county of Essex and State of Massachusetts, have invented and produced a new and original Design for an Indicator-Body, of which the following is a specification.

Reference is to be had to the accompanying drawing, forming a part of this specification, in which the figure shows a perspective view of an indicator-body embodying my new design.

The essential feature of the design consists in the body having the configuration of a shield and surmounted by a cross.

A indicates the shield-like body, and b the cross surmounting the same.

The minor features of the design are the plain arms c, terminating in rounded knobs d, projecting at right angles to the arms. 20

I claim—

The design for an indicator-body, herein shown and described.

WILLIAM D. KAIN.
